EX

DESIGN.

—o—
W. C. HANNA, Jr.

STABLE HINGE.

No. 16,349

Patented Oct. 27, 1885.

UNITED STATES PATENT OFFICE.

WILLIAM CAMERON HANNA, JR., OF NEW YORK, N. Y., ASSIGNOR TO J. W. FISKE, OF SAME PLACE.

DESIGN FOR A STABLE-HINGE.

SPECIFICATION forming part of Design No. 16,349, dated October 27, 1885.

Application filed May 21, 1885. Serial No. 166,326. Term of patent 7 years.

To all whom it may concern:

Be it known that I, WILLIAM C. HANNA, Jr., of New York, in the county of New York and State of New York, have invented a Design 5 for Stable-Hinges, of which the following is a specification.

This invention consists in a novel design for the ornamentation of stable-hinges, as herein-after more fully set forth, and as shown in the 10 accompanying photograph, which is a front or face view of a hinge embodying my design. The hinge is in the form or style of what is known as a "strap-hinge," A representing the shorter and B the longer arm of the hinge.

15 The design consists of a series of raised figures, *e*, in the form of horseshoes, which may be grouped or arranged in the manner shown in the accompanying photograph, or in any manner which will present to the eye substantially the same appearance. As shown in 20 the photograph, it will be seen that the figures *e* on the longer arm, A, of the hinge are arranged so as to point all in one direction, and are made to lap one upon another, while on 25 the shorter arm, B, of the hinge they are arranged with the toes of the shoes pointing in opposite directions.

The particular arrangement of the shoes upon the two arms of the hinge may be varied without changing the character of the design, 30 the essential feature of which is the series of figures or shoes *e* upon the face or outer surface of the hinge. I have also shown a raised border, *a*, along each edge of the arms A and B, and have also shown a series of bosses or 35 knobs, *e*, located at intervals in said border; but this feature, while rendering the hinge more ornamental, may be omitted without materially changing the appearance, if desired.

What I claim is—

1. The design for a hinge herein shown and described, the same consisting of the straps or arms A and B, having a series of figures representing horseshoes upon their exterior or front surface. 40
2. The design for a hinge, consisting of the straps or arms A and B, having a series of figures representing horseshoes, and a border, *a*, surrounding or inclosing the shoes, as shown and described. 45

WILLIAM CAMERON HANNA, JR.
